CASEMENT WINDOW

Filed June 30, 1928.

Inventor

T. Johnson

By Watson E. Coleman
Attorney

UNITED STATES PATENT OFFICE

THEODORE JOHNSON, OF ERIE, PENNSYLVANIA, ASSIGNOR TO JOHNSON METAL PRODUCTS CO., OF ERIE, PENNSYLVANIA

CASEMENT WINDOW

Application filed June 30, 1928. Serial No. 289,533.

This invention relates to casement window fastener and has relation more particularly to a structure of this kind of a single casement type, and it is an object of the invention

5 to provide novel and improved means whereby the swinging window sash may be effectively held with respect to the window frame.

Another object of the invention is to provide a device of this kind wherein the fastener member is carried by the member of the frame at a point inwardly of said frame for holding engagement with the out swinging member of the sash when the sash is in closed position with respect to the frame.

15 The invention consists in the details of construction and in the combination and arrangement of the several parts of my improved casement window fastener whereby certain important advantages are attained 20 and the device rendered simpler, less expensive and otherwise more convenient and advantageous for use, as will be hereinafter more fully set forth.

The novel features of my invention will 25 hereinafter be definitely claimed.

In order that my invention may be the better understood, I will now proceed to describe the same with reference to the accompanying drawings, wherein:—

30 Figure 1 is a view partly in section and partly in top plan illustrating a fastening means for a casement window constructed in accordance with an embodiment of my invention;

35 Figure 2 is a fragmentary view in perspective illustrating coacting members of the window casement and frame and certain of the parts comprised in the fastening means directly associated therewith;

40 Figure 3 is a view in rear elevation illustrating the fastener means as herein disclosed;

Figure 4 is a view in perspective of the lug for attachment to the window sash as herein 45 employed.

As disclosed in the accompanying drawings, F denotes a casement frame of requisite dimensions and design and which is adapted to have associated therewith a single window sash W. This sash W is adapted to be

hingedly connected in a well known manner with a side or vertical member of the frame for outward swinging movement with respect to the frame.

The vertical member 1 of the frame F adjacent to the out swinging member 1^a of the sash W at a desired point thereon, and preferably substantially midway of its ends, has anchored thereto by the screws 2 or the like an end portion of a plate 3 extending within the light area of the frame F and also extending inwardly beyond said out swinging member 1^a when the sash is in closed position.

The extended portion of the plate 3 or that portion within the light area of the frame F is provided with an opening 4 through which is directed a shank 5 carried by the central portion of the inner face of a head 6. This shank 5 extends inwardly beyond the plate 3 and to said extended portion is suitably affixed a fastener member or disc 7. This disc 7 has an arcuate beveled marginal portion 8 substantially equal to a quarter of a circle, said beveled marginal portion 8 constituting the working face of the disc 7.

The periphery of the disc 7 immediately adjacent to one end of the face 8 is provided with an arcuate recess 9 providing spaced shoulders 10 which are adapted to have contact with a pin 11 extending outwardly from the inner face of the plate 3 whereby the extent of rotation of the disc 7 in either direction is positively limited.

The opposite end portion of the beveled working face 8 of the disc 7 is continued by a straight face 12 and so spaced with respect to the axial center of the disc as to assure said disc 7 being entirely free of the out swinging member 1^a of the sash W when the disc 7 has been turned to the limit of its movement in one direction.

Secured by the screws 14 or the like to the inner marginal portion of the out swinging member of the sash W is an elongated lug 15. This lug 15 has a longitudinal marginal portion projecting beyond the adjacent marginal portion of the out swinging member of the sash and said marginal portion of the lug 15 is disposed on an inward bevel 16 com-

plemental to the bevel of the working face 8 of the disc 7.

When the window sash W is in its fully closed position, the extended portion of the plate 3 is disposed over the applied lug 15 and upon requisite turning movement of the disc 7 the working beveled face 8 thereof will have close contact with the beveled face 16 of the lug 15 and thereby effectively hold the sash tightly in its closed position.

The head 6 has pivotally connected therewith, as at 17, an elongated arcuate handle 18 which provides convenient means for effecting the desired rotation of the head 6 and the associated disc 7 for holding or releasing the window sash as desired. In this operation, the handle 18 may be readily swung outwardly to assure an effective leverage action.

In applying the screen to the frame F said screen may have produced therein a suitable opening 19 through which the head 6 will be disposed. In applying or removing the screen S the handle 18 may be readily swung into a position constituting substantially a continuity of the outer end of the head 6, said handle 18 being disposed lengthwise on a curvature to permit the screen S to be readily swung upon its lower edge as a fulcrum.

This latter feature is particularly described and illustrated in my pending application Serial No. 253,744 of which the present invention is an improvement.

From the foregoing description it is thought to be obvious that a casement window fastener constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In combination with a window frame and a sash coating therewith, a plate secured to a member of the frame and disposed inwardly thereof, said plate overlapping a marginal portion of the sash when the sash is in closed position with respect to the frame, a fastener member rotatably carried by the extended portion of the plate, means carried by the portion of the sash adjacent to the member of the frame carrying the plate with which the fastener member is engageable to hold the sash in closed position with respect to the frame, and coating means carried by the extended portion of the plate and the disc for limiting the movement of the fastener member in opposite directions.
2. In combination with a window frame

and a sash coating therewith, a plate secured to a member of the frame and disposed inwardly thereof, said plate overlapping a marginal portion of the sash when the sash is in closed position with respect to the frame, a fastener member rotatably carried by the extended portion of the plate, said fastener member having a beveled marginal portion constituting a working face, and a member carried by the window sash and having a marginal portion beveled complementary to the beveled working face of the fastener member and with which said beveled working face of the fastener member engages upon turning movement of the fastener member in one direction to lock the sash in closed position with respect to the frame.

3. A casement window fastener comprising a plate adapted to be connected to a window frame with an end portion extending within the light area of the frame to overlie a window sash when the sash is in closed position with respect to the frame, and a fastener member carried by said end portion of the plate for holding engagement with the sash when closed.

4. A casement window fastener comprising a plate adapted to be connected to a window frame with an end portion extending within the light area of the frame to overlie a window sash when the sash is in closed position with respect to the frame, a fastener member carried by said end portion of the plate for holding engagement with the sash when closed, said fastener member being at the side of the plate opposed to the sash, and means at the opposite side of the plate for operating said fastener member.

5. A casement window fastener comprising a plate adapted to be connected to a window frame with an end portion extending within the light area of the frame to overlie a window sash when the sash is in closed position with respect to the frame, a shank disposed through and rotatably supported by said end portion of the plate, a fastener member at one side of the plate and rotating with the shank, said member upon rotation of the shank in one direction being engageable with the sash to hold the same in closed position, and an operating handle for the shank at the opposite side of the plate and pivotally connected to the shank.

6. A latching means adapted for use with a support and a swinging member comprising a shank directed through and rotatably supported by the support, an approximately semi-circular disc carried by the shank for engagement with the swinging member to hold the same when said swinging member is at the limit of its movement toward the support, said disc having a substantially straight portion to permit the member to be swung away from the support when the

disc is in a second position, the axis of the disc being disposed in the same general direction as the swinging movement of the member, and an operating member hingedly connected with the shank at the side of the support remote from the disc.

5 In testimony whereof I hereunto affix my signature.

THEODORE JOHNSON.
